CLAIM

The ornamental design for a slide clip, as shown and described.

DESCRIPTION

FIG. 1 is a top perspective view of a slide clip, showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective assembly view of the slide clip of FIG. 1 installed in an exemplary wall assembly.

The slot shown in dashed lines in FIGS. 1, 3, 4, and 9 and the fasteners and elements of the wall assembly shown in dashed lines in FIG. 9 are unclaimed subject matter and form no part of the claimed design.
